UNITED STATES PATENT OFFICE.

FREDERICK RICHARD WEBB, OF RANDALSTOWN, IRELAND.

APPARATUS FOR THE PRODUCTION OF PERIODIC LARGE-VOLUME DISCHARGES OF LIQUIDS.

Application filed October 30, 1920, Serial No. 420,665, and in Great Britain January 7, 1920.

This invention relates to an apparatus for applying the liquid in liquid-purification processes such as mechanical filtration and the like, and comprises a method whereby the normally continuous flow (of the liquid) as employed in these processes, is converted to a series of periodic discharges of comparatively large volume and high velocity at regular intervals, in such a manner and of such a character as to act towards increasing the efficiency of such processes.

Other uses to which the apparatus may be put with advantage are in connection with flushing systems for lavatories and the like.

Provision is made for charging the receptacle with the requisite amount of air prior to its operation; provision is made to preclude any possibility of leakage from the air charge in the receptacle to the atmosphere since it is necessary for the apparatus to operate on its initial air-charge for extended periods without recharge.

Provision is also made for producing a very rapid closing-movement of the discharge valve when the time arrives and also for maintaining a thorough closure of said valve against the liquid under pressure in the receptacle during the time that the aforementioned pressure is accumulating therein.

This invention consists in the provision of the apparatus by which these periodic large-volume discharges of liquids are produced or furnished and which is defined in the claims that follow hereinafter and of which there are illustrated in the accompanying drawings, by way of example, three different forms of construction according to the present invention. In the drawings illustrating the principle of this invention and the best mode now known to me of applying that principle;

Figure 1 shows a view of one form of the apparatus just before discharging.

Figure 2 shows a similar view just before the closure of the discharge valve.

Figure 3 shows a section of a modified form of construction with the discharge valve closed.

Figure 4 shows a similar view during discharge.

And Figure 5 shows an auxiliary apparatus for controlling the discharge of the main receptacle.

Referring now to Figures 1 and 2, the re-

ceptacle 1 is in the form of an upright cylinder closed at its upper end and of a substantially larger bore than that of the pipeline of the water-service (i. e., the supply-conduit 2). The upper portion of the cylinder is gas-tight and consequently suitable for the compression and retention of an elastic fluid (air) by liquid (water) furnished by the supply-conduit 2. In the side of the said receptacle 1 and near the foot thereof an inlet bore is formed, at which point the supply-conduit 2 is connected in a watertight manner, a suitable valve 3 therein being provided for controlling the admission of water to the receptacle 1. On or near the upper end of the receptacle 1, a cock 4 is arranged for the admission of air, or for regulation of the amount of air enclosed, preparatory to the operation of the device; whilst in the lower end a drain-cock 5 is provided for reducing the water contents of the receptacle if desired; both cocks 4 and 5 being closed whilst the device is in operation.

In the bottom of the receptacle a bore is formed at 6 preferably concentric with the receptacle, this bore serving to receive a valve-seat or socket member 7. This socket member comprises an annular disc 8 from which project two concentric cylinders 9 and 10. The cylinder 9 serves as the discharge-outlet from the receptacle 1 and its bore is considerably less than that of the cylinder 10. The smaller cylinder 9 is shorter in length than the larger cylinder 10, and its lower end is finished to form a seating for a disc valve 11 which is a sliding fit in the larger cylinder 10. The valve 11 is suitably guided; for example by means of spider arms 12. The bore of the lower part of the larger cylinder 10 is further enlarged so that, when the disc valve has moved off its seating for a certain distance, there is sufficient clearance to allow of the free flow of the water past the valve. A disc 13 of suitable jointing material, such as fibre or the like, may be interposed between the valve and its seating in order to ensure against leakage of water past the seating when the valve is closed. A central hole is formed in the piston valve 11, and a rod 14 threaded therethrough; the lower end of the rod is formed with a head 15 for holding the disc valve 11 in position, while suitable jointing material is interposed between the valve and its head. This rod is preferably slidable

relatively to the disc valve. The other end of the rod passes through a central hole formed in the upper end of the receptacle, and suitable packing means, such as gland members, are provided to prevent the escape of air.

In a preferred form the gland member 16 has a hollow cylindrical member 17 formed at its upper end. The valve 11 is normally held against its seat by suitable means; as, for example, a spring 18 disposed inside the cylindrical member 17. The lower end of the spring 18 abuts against a second gland member 19 and its upper end bears against an adjustable collet 20 in threaded engagement with the rod 14. By adjusting the collet 20, the pressures at which the disc valve 11 will operate may be varied as desired. A further adjustable abutment member is provided on an extension 22 of the adjustable collet 20 and is in threaded engagement therewith and is adapted to abut against the upper end of the cylinder 17, at a predetermined point during the opening movement, in order to prevent excessive dropping of the disc valve 11. The cylinder 17 enclosing the aforesaid spring 18 may contain oil, and a cap may be provided to close in or house this part of the apparatus.

In order to obtain a very rapid closure of the discharge orifice after a predetermined volume of water has been discharged, and to prevent the withdrawal of air from the receptacle through the said discharge orifice which may occur under exceptional circumstances, a float-controlled disc-valve 25 is slidably mounted on the valve rod 14. The diameter of the disc valve 25 is such that the valve serves fully to cover the upper orifice of the discharge-outlet-cylinder 9. The disc valve 25 is connected to a float 26, which controls its movement. It will be seen that, as the water level falls, the disc valve 25 will eventually cover the outlet orifice and so prevent further flow of water.

The operation of the apparatus is as follows: Assume the tension on the spring 18 has been set so that the disc valve 11 will open when the pressure of the water has reached a predetermined point. The air inlet cock 4 is opened and the receptacle drained of any residual water it may contain through the drain cock 5. The drain cock 5 and air cock 4 are then closed, and water allowed to enter the receptacle through the inlet 2 near the lower part thereof. The level of the water pouring into the receptacle 1 will continue to rise and, at the same time, compress the air above it until the required fluid pressure is reached, which may be taken to be, for example, when the volume of the air is half its original volume, when the disc valve 11 will begin to open against the action of the spring 18 holding it on its seat.

Water under pressure will now fill the

space between the upper end of the larger cylinder 10 and the outer portion of the disc-valve 11, and since the area of the disc valve 11 is considerably greater than the area of the orifice covered by the valve when closed, the valve spring 18 as a consequence will yield suddenly under the considerably increased pressure to which it is thus subjected, and a discharge will take place through the annular space between the cylinder 10 and the disc-valve 11 in its dropped position.

It is obvious that as the disc-valve 11, in its downward movement, enters the enlarged portion of the bore of the cylinder 10, the fluid force, acting downwardly upon it, will be so considerably diminished when that point is reached in the movement at which the abutment member 21 strikes the upper end of the cylinder 17, that little or no shock will occur at this point; and it will also be obvious that under certain conditions the said fluid force will be so reduced as to be balanced by the opposing force of spring 18, even before this striking point is reached at all.

As the water level drops inside the receptacle 1, the float-valve 25 will approach the outlet orifice, until finally the suction of the water causes it to close down quickly upon the outlet orifice, thus effecting a sudden stoppage of the discharge. The disc valve 11 will now lift under force of the spring 18 and will again cover the outlet-orifice, displacing as it does so the water from above it through the annular clearance space surrounding its periphery, with the result that the pressures on either side of the float valve 25 will be equalized; the float 26 will then lift the valve 25 thus uncovering the outlet orifice in preparation for the next discharge, and the cycle of operations will begin again.

Thus an intermittent discharge of a relatively large volume of water at high pressure is obtained on the ordinary pipe line of the water service; and it is obvious that once the apparatus has been started in operation, the quantity of water discharged at each impulse can, by opening the air cock 4 and thereby allowing a portion of the air contents of the receptacle 1 to escape, be reduced to any reasonable extent desired; and the frequency of the discharges may, as a necessary result or consequence following therefrom, be likewise increased; and again the frequency of the discharges may, by throttling the inlet 2, be decreased to any reasonable extent desired. It is obvious also that the intensity (e. g. rate of flow per second) of each discharge may, by adjusting the spring 18 to a higher tension, be increased to any reasonable extent desired.

From what has been set forth it will be clear that by suitably manipulating the

spring 18, the air-cock 4, or the pipe line (or) works in a cylinder 32 mounted on the upper inlet) valve 3 (or as many of these elements per end of the receptacle 1. The piston-rod 30 is guided in a tube 33 which is connected to the receptacle 1 by an air-tight joint or is formed integral therewith, as shown. Near its upper and lower ends, the piston-rod 30 is provided with ports 34, 35, respectively, so as to allow the passage of fluid (e. g., water) through the piston-rod 30 from the receptacle 1 to the cylinder 32 in which the water, trapped between the float-disc 25 and piston 31 works and vice versa. Near the lower end of the tube 33, there is provided a sleeve or bush 36 which is adapted to close the ports near the lower end of the piston-rod 30 shortly before the valve 29 has reached the limit of its upward movement. The valve 29 is suitably loaded so as to be held normally closed; as, for example, by the pressure of a spring 37 acting upon the piston 31.

In order to preserve the spring 37 from risk of corrosion, the piston 31 is preferably formed as a cylinder 39 that is open at its top end and contains oil. An annular groove 40 is formed in the interior of the cylindrical wall of the housing 32, and, through vents 41, this groove 40 communicates with the outside or exterior of the housing and serves as a conduit for any water which may find its way between the piston 31 and its housing 32.

In order absolutely to prevent any leakage of air past the valve-rod, the gland member 23 through which the rod passes is preferably formed with a downward tubular extension 24 projecting to the lowest possible level in the receptacle, the float controlled valve being arranged around this tubular stem. In those cases in which a very sudden exposure and closure of the discharge outlet is not of paramount importance, it is obvious that the valve 25, together with its operating float 26, may be dispensed with so that the closure will occur as soon as the discharge of water through the annular space surrounding the periphery of the valve disc 11 has so depleted the water contents of the receptacle 1, and as a consequence expanded its air contents, that the fluid pressure acting downwardly upon the full area of the said valve disc 11, is over-balanced by the closure force of the spring 18.

The apparatus above described is described merely by way of example and the invention is not limited to the particular form of construction set forth which may be modified or varied to suit the particular circumstances for which the apparatus is required.

Such a modified form of this invention will now be described.

Referring to Figures 3 and 4, the receptacle 1 is similar in form to that shown in Figures 1 and 2 and is provided with the air-cock 4, the drain-cock 5 and the water-inlet 2. In the base of the receptacle 1, there is provided an outlet-orifice in which there is mounted a nipple 27 by means of which the apparatus can be connected to the filter or other apparatus to be flushed. Around the outlet-orifice, there is provided a valve-seat 28 for a valve 29 connected by a hollow piston-rod 30 to a piston 31 which

works in the cylinder 32. The piston-rod 30 is guided in a tube 33 which is connected to the receptacle 1 by an air-tight joint or is formed integral therewith, as shown. Near its upper and lower ends, the piston-rod 30 is provided with ports 34, 35, respectively, so as to allow the passage of fluid (e. g., water) through the piston-rod 30 from the receptacle 1 to the cylinder 32 in which the water, trapped between the float-disc 25 and piston 31 works and vice versa. Near the lower end of the tube 33, there is provided a sleeve or bush 36 which is adapted to close the ports near the lower end of the piston-rod 30 shortly before the valve 29 has reached the limit of its upward movement. The valve 29 is suitably loaded so as to be held normally closed; as, for example, by the pressure of a spring 37 acting upon the piston 31.

In order to preserve the spring 37 from risk of corrosion, the piston 31 is preferably formed as a cylinder 39 that is open at its top end and contains oil. An annular groove 40 is formed in the interior of the cylindrical wall of the housing 32, and, through vents 41, this groove 40 communicates with the outside or exterior of the housing and serves as a conduit for any water which may find its way between the piston 31 and its housing 32.

The spring 37 then works in the oil inside the cylindrical extension 39 of the piston, whilst it bears at the top against the tubular abutment 38, over which the cylindrical extension 39 of the piston slides. The lower face of the valve 29 may be provided with a rubber washer 42 so as to take up the shock when the valve closes. Further, as regards the piston 31, Figures 3 and 4, the lower end is preferably provided with a depending rim 31^a so as to form a receptacle to trap air and constitute an air cushion. This air cushion is adapted to absorb the shock (or water hammer) which occurs when valve 29 closes; for the liquid suddenly rushes upwards through the hollow piston rod 30, when the valve begins to close, and tends to lift the piston 31 and start a series of oscillations of the valve 29, viz., opening and closing it to a small extent at rapid intervals.

The operation of the apparatus illustrated in Figures 3 and 4 is as follows:

Assume the tension on the spring 37 to be such that the disc valve will open when the pressure of the water has reached a predetermined point, (say, 20 lbs. per sq. in.). The air cock 4 is opened and the receptacle drained of any residual water it may contain; the drain cock 5 and the air cock 4 are then closed, and water is allowed to enter the receptacle through the inlet 2 at the lower part thereof.

This water will gradually compress the

air in the receptacle 1 whilst at the same time a portion of it will by-pass, through the pressure exerted by the spring 44 the piston hollow piston-rod 30, from the receptacle 1. 46 will be pressed downwards by the spring 44 and close the valves 3^x and 43. 5 therein upwardly past the piston 31. The incoming flow of water to the receptacle 1 will continue compressing the air therein with the result that eventually the fluid pressure that acts on the upper face of the valve 29 and that tends to hold it on its seat 28, plus the pressure of the spring 37 on the piston 31, will just balance the upward fluid pressure on the piston 31, the area of which is larger than that of the valve 29. Then, 15 as soon as the upward fluid pressure acting on the piston 31 is increased slightly, the piston will be forced upwards in its cylinder 32 and will open the valve 29 so that a rapid discharge of liquid will take place through 20 the outlet orifice. Directly the valve 29 lifts from its seating, the liquid pressure which was formerly acting on its upper face to keep the valve closed, will, of course be balanced by the liquid pressure now acting on 25 its exposed under-face, so that the valve will remain open whilst the discharge takes place and in spite of the diminishing fluid pressure in the receptacle. The discharge will continue until this fluid pressure acting upwardly upon the same is no longer able to hold the piston 31 against the downward pressure of the spring 37 acting thereon, whereupon the valve 29 closes. 30 Water will now rise slowly in the receptacle again, until such pressure-conditions are reached as to cause the valve 29 to open for a further discharge and continue the process.

In Figure 5, there is illustrated a modified form of this invention, wherein the mechanism by means of which the valve 3^x controlling the outlet from the main air-vessel 1 is operated, is arranged external thereto. The liquid is led to the main receptacle or air-vessel 1 through the conduit 27 and flows from the air-vessel 1 through the discharge pipe 2^x, the flow being controlled, in the latter pipe, by the valve 3^x. An inlet-pipe 27^x, which is by-passed from the main inlet-pipe 27, conveys liquid to a suitable receptacle 49, provided with an air-cock 4 and drain-cock 5.

The valve 43 in this construction is loaded, for example by means of a spring 44, mounted in a cylindrical portion 45 of the receptacle 49, and acting on a piston 46. The piston rod 47, which connects the piston 46 to the valve 43, has its upper end connected to a lever 48 for operating the main valve 3^x. When a predetermined pressure is reached inside the receptacle 49, the piston 46 will rise in the cylinder 45, against the action of the spring 44, and open the valves 3^x and 43, thus discharging the main receptacle 1. As soon as the pressure inside

The devices hereinbefore described may be fitted to a tank of any size according to the amount of flushing water required at each discharge.

Having thus described my invention what I claim as new and desire to secure by Letters Patent is:—

1. An apparatus of the character described comprising a receptacle suitable for the compression of an air-charge by a liquid and provided with an inlet conduit and an outlet conduit for the liquid; means for precluding leakage of the air-charge from the receptacle so that said charge can be repeatedly used without diminution; a loaded valve which normally closes the outlet conduit; means, operated by the liquid under pressure of the air-charge in the receptacle, for opening the valve when a predetermined degree of air-compression is attained; and means depending upon the loading force for returning the valve to the closed position when a predetermined amount of liquid has been discharged through the outlet conduit.

2. An apparatus of the character described comprising a receptacle suitable for the compression of an air-charge by a liquid, and provided with means of ingress and means of egress for the liquid; means for precluding leakage of the air-charge from the receptacle, so that the said charge can be repeatedly used without diminution; a loaded valve which normally closes the means of egress whilst the liquid, under pressure of the air-charge in the receptacle, acts, in opposition to the loading force, upon a surface of varying effectiveness, towards opening the said valve; means dependent upon the fluid pressure in the receptacle, for over-balancing the loading force, so as to open the valve and increase the effectiveness of the said surface, when a predetermined degree of air-compression is attained; and means dependent upon the loading force for over-balancing the fluid pressure and returning the valve to the closed position, when a predetermined amount of liquid has been discharged, through the said means of egress so that the effectiveness of the said surface is again reduced.

3. An apparatus of the character described, comprising a receptacle suitable for the compression of an air-charge by a liquid and provided with means of ingress and means of egress for the liquid; means for precluding leakage of the air-charge from the receptacle so that said charge can be repeatedly used without diminution; a loaded valve which normally closes the means of egress; a piston which is arranged to operate the loaded valve and the area of which

is larger than that of the valve-seat, said piston being operated by a liquid under pressure of the air in the receptacle; and a cylinder in which the piston reciprocates and which is in liquid communication with the receptacle; the piston being arranged to open the valve against the load thereon when a predetermined pressure is reached in the receptacle, and the valve being arranged to close automatically when a predetermined amount of liquid has been discharged from the receptacle.

4. An apparatus of the character described, comprising a receptacle suitable for the compression of an air-charge by a liquid and provided with means of ingress and means of egress for the liquid, means for precluding leakage of the air-charge from the receptacle so that said charge can be repeatedly used without diminution; a valve arranged to close the means of egress; a cylinder attached to the receptacle and which communicates with the liquid contained therein; a piston which works in the cylinder and operates the valve and the area of which is larger than that of the valve-seat; and a spring which acts upon the valve so as to hold it normally closed.

5. An apparatus of the character described, comprising a receptacle suitable for the compression of an air-charge by a liquid and provided with means of ingress and means of egress for the liquid; means for precluding leakage of the air-charge from the receptacle so that said charge can be repeatedly used without diminution; a valve loaded with a view to closing the means of egress; a piston, dependent for its operation upon the air-pressure in the receptacle, for opening said valve when a predetermined degree of compression is attained, said piston communicating with the contents of the receptacle at a point below the air-charge therein contained; and means dependent upon the loading-force, for returning the valve to the closed position when a predetermined amount of liquid has been discharged from the receptacle through the means of egress.

6. An apparatus of the character described, comprising an air-tight receptacle containing a predetermined volume of air and having an inlet conduit through which a small current of water is fed continuously for the purpose of compressing said air, and an outlet conduit for the purpose of discharging the water periodically, and at regular intervals, under influence of the air thus compressed; a valve controlling the outlet conduit, the valve being held on its seat by means of a spring; a piston hydraulically operated, under influence of the fluid-pressure accumulated in the receptacle, towards unseating the valve, said piston being in communication with the water contents of

the receptacle and so arranged that it is only partially effective when the valve is seated, but is increasingly effective as the valve leaves its seat, so that at a predetermined degree of air-compression in the receptacle the valve is opened and, due to the increased effectiveness of the piston thus produced, maintained open against the spring; and means dependent upon the spring for returning the valve to the closed position as soon as a predetermined amount of water has been discharged through the outlet conduit, so that the effectiveness of said piston is again reduced, and so maintained until the predetermined degree of air-compression is again reached within the receptacle and the valve is again forced from its seat.

7. An apparatus of the character described, comprising a receptacle suitable for the compression of an air-charge by a liquid and provided with means of ingress and means of egress for the liquid; a valve arranged to close the means of egress; a cylinder attached to the receptacle, the bore of the cylinder being greater than that of the valve-seat; means for precluding access of the air-charge to the cylinder; a piston arranged to reciprocate in the cylinder, the piston being attached to the valve and operating to open it; and a spring which operates to close the valve.

8. An apparatus of the character described, comprising a receptacle containing a charge of air adapted to be compressed by a liquid, with means precluding leakage of said air-charge from the receptacle and means of ingress and means of egress for the liquid; a valve controlling the means of egress; a piston controlling the valve; the liquid, under influence of the air-charge in the receptacle, operating upon the piston to open the valve when a predetermined compression of the air-charge has been attained; whilst an opposing force operates upon the piston, to return the valve to the closed position as soon as a predetermined amount of liquid has been discharged from the receptacle past the valve, said closure being arranged to take place whilst the pressure of the air-charge is still in excess of atmospheric pressure; and said opposing force operating upon said piston to maintain the valve in the closed position so that the predetermined compression of the air-charge can be again attained preparatory to the next discharge.

9. An apparatus of the character described comprising an air-compression-chamber containing an air-charge and provided with means of ingress for a liquid to compress said air-charge and means of egress to discharge the liquid, thus accumulated, periodically and at regular intervals; means precluding leakage of the air-charge

- from the compression-chamber so that said charge can be repeatedly used without diminution; a loaded valve which normally closes the means of egress, whilst the fluid-pressure, due to compression of the air-charge, acts, with varying effectiveness, in opposition to the loading-force, towards opening the valve; means for increasing the effectiveness of said fluid-pressure so as to 5 overbalance the loading force and open the valve; means for further increasing the effectiveness of said fluid-pressure so as to maintain the valve fully open for an appreciable period to permit of a discharge from 10 the compression-chamber; means for reducing the effectiveness of said fluid-pressure so that the force produced thereby is overbalanced by the loading-force which then returns the valve to the closed position; and 15 means for further reducing the effectiveness of said fluid-pressure so as to enable the loading force to maintain the valve closed for an appreciable period to permit of a recharge of liquid to the compression-chamber. 20
10. An apparatus of the character described comprising an air-compression chamber containing an air charge and provided with means of ingress for a liquid to 25 compress said air-charge and means of egress to discharge the liquid, thus accumulated,
- periodically and at regular intervals; means precluding leakage of the air-charge from the compression chamber so that said charge can be repeatedly used without diminution; 35 a loaded valve which normally closes the means of egress, whilst the fluid-pressure, due to compression of the air-charge, acts, with varying effectiveness, in opposition to the loading force, towards opening the 40 valve; means for increasing the effectiveness of said fluid-pressure so as to overbalance the loading force and unseat the valve; means for further increasing the effectiveness of said fluid-pressure so as to force said 45 valve rapidly towards the fully open position; means for reducing the effectiveness of said fluid-pressure as the valve approaches the fully open position so that said position is attained without shock; means for further reducing the effectiveness of said fluid-pressure so that the force produced thereby is overbalanced by the loading force which then returns the valve to the closed 50 position; and means for still further reducing the effectiveness of said fluid-pressure so as to enable the loading force to maintain the valve closed for an appreciable period to permit of a recharge of liquid to the compression-chamber. 55

FREDERICK RICHARD WEBB.
